UNITED STATES PATENT OFFICE.

EUGÈNE DERVAL, OF PARIS, FRANCE.

REGENERATIVE GAS-FURNACE.

SPECIFICATION forming part of Letters Patent No. 653,793, dated July 17, 1900.

Application filed May 9, 1899. Serial No. 716,138. (No model.)

To all whom it may concern:

Be it known that I, EUGÈNE DERVAL, engineer, of 18 Rue Mogador, Paris, in the Republic of France, have invented an Improvement in Regenerative Gas-Furnaces; and I do hereby declare the nature of this invention and in what manner the same is to be performed to be particularly described and ascertained in and by the following statement.

This invention relates to improvements in the furnaces of inclined retorts, the object of which is to improve the working and reduce the cost.

The accompanying sheet of drawings illustrates the application of the said improvements to a bench of nine retorts for making illuminating-gas, it being understood that the construction and arrangement of the furnace may be varied according to the number, shape, and dimensions of the retorts employed.

In the said sheet of drawings, Figure 1 is a longitudinal section through the center of a bench of retorts; Fig. 2, a section taken through one of the regenerators of the furnace. Fig. 3 shows four half-transverse sections taken on the lines A A, B B, C C, and D D of Fig. 2; and Fig. 4 shows four half-horizontal sections taken on the lines M M, N N, O O, and P P of Fig. 2.

The arrows *a* indicate the course taken by the air necessary to effect combustion of the gas generated in the gas-producer I, and the arrows *b* the course taken by the said gas on its way out of the said gas-producer. The arrows without an indicating-letter show the course taken by the products of combustion.

1 indicates the combustible gas-producer, fed with coke or coal; 2, the charging-throat of the gas-producer; 3, the regenerator for utilizing the waste heat of the products of combustion in order to heat the air necessary for the combustion of the gas generated in the producer; 4, the damper; 5, the combustion-chamber; 6, the flue leading to the chimney; 7, the first inlet for hot air into the combustion-chamber; 8, the second inlet for hot air near the middle of the retorts; 9, the small inlet for air for reheating, when necessary, the gas from the producer; 10, retorts made slightly conical; 11, a stopper for retaining the coal charged into the retort; 12, a cement covering for the front of the furnace; 13, in-

clined pipes for conducting the gas from the inclined retorts to the hydraulic main; 14, a hydraulic main.

In the drawings the retorts are shown inclined at an angle of thirty-two degrees; but this inclination may be varied between twenty-eight degrees and thirty-six degrees, and even more, according to the nature of the coal, the method of charging, and the shape and the length of the retorts. The inclination of thirty-two degrees to thirty-four degrees should be considered as a medium inclination corresponding tolerably well to the conditions required for a good distillation of the coal and an easy discharge of the coke.

Since their introduction for the manufacture of illuminating-gas inclined retorts have not given very good results, chiefly in consequence of the difficulty of heating them economically and regularly. Furthermore, the necessity there has been of placing the combustible gas-producer in such position that it projects beyond the retort-bench in order to have space enough for the regenerators and the smoke-flue has rendered it very difficult to construct the furnaces properly. In some installations the charging of the producer and the cleaning of the fire-bars has been done, as in my furnaces, behind the retort-benches; but it has then been necessary to make use of a special floor or platform for charging the producers, so that there were required three different floors or platforms—one for charging the retorts, one for charging the producers, and one for discharging the coke.

Furnaces constructed according to my invention allow the height of the bench of retorts to be greatly reduced and the floors or platforms for discharging the coke and for charging the producers to be done away with without its being necessary to have a special pit for clearing the grate-bars. The removal of ashes and clinker is effected at the level of the floor of the retort-house; but a pit may be made, if preferred, behind the benches.

In order to charge the producers from the same charging floor or platform as the retorts, I simply do away with the arch over the producer and use instead thereof the bottom of the middle retort. When the quality of the retorts is not quite certain, it is preferable to

support the bottom of this retort on a row of fire-clay slabs, as shown in the drawings. This arrangement is a special feature of my invention which, combined with my system 5 of burner or gas-producer, has enabled me to reduce considerably the cost of inclined retort-furnaces by placing the producer and the regenerators in the space left by the inclination of the retorts.

10 The retorts are supported by transverse walls placed so that the flames or hot products of combustion follow the course shown by the arrows in the drawings.

15 The circulation of the flames or hot products of combustion in the direction indicated—that is to say, lengthwise of the retorts—is assured by a cross-wall M, which rises up to the arch of the furnace, so as to return the flames or hot products of combustion under 20 the lower retorts.

Contrary to the usual practice the regenerator is so arranged that the smoke and waste products of combustion pass into the vertical holes of the brickwork of the regenerator; but this arrangement is not indispensable and any other system of regenerator 25 may be employed for heating the air.

The construction of the gas-producer may of course be modified, according to the nature 30 of the fuel employed, without departing from my invention.

An examination of Figs. 1, 3, and 4 shows easily that the gas which escapes from the gas-generator and passes by the apertures o, 35 arranged at the upper part of the wall N, can be carried to as high a temperature as may be desired by the introduction of a sufficient quantity of air into the principal combustion-chamber 5, said introduction taking place at

40 7. As this combustion-chamber is placed below the lowest extremity of the retort which covers the gas-generator it will always be possible to bring the base of the retorts to the desired temperature by regulating, through

45 the air-valve y of the recuperator, the admission of hot air taking place at 7. As regards the upper part, which does not require to be raised to so high a temperature for a good distillation, it is only necessary to open ap-

50 propriately the damper X, which regulates the second inlet of hot air at 8. (See Fig. 2.) The small inlets for air, (shown at 9,) one at each side of the charging-opening of the gas-producer, are simply for partly turning the

55 gas in the producer when, for example, in consequence of the employment of coal as fuel the distillation is not perfect in the retort placed directly over the producer. I attach great importance to the use of this ar-

60 rangement of furnace, for it enables me to obtain not only a very regular heating of the retorts with coke, coal, or tar, but also a notable reduction of the quantity of fuel consumed in consequence of the better utilization

65 of the heat of the flame or of the products of combustion. Furthermore, the suc-

cessive combustion to which I subject the gases before sending them to the regenerator prevents the cutting action of the fire on the retorts, and the duration of the latter is thereby increased. This method of heating may also be applied to furnaces of seven and eight retorts, also to furnaces having only two vertical rows of retorts, (furnaces with two, five, and six retorts.) In this latter case the gas-producer is placed at the side of the furnace under one of the lower retorts. For furnaces having two horizontal rows of retorts it is sufficient to omit in furnaces with seven, eight, and nine retorts the second row of retorts 80 without altering the furnace at all or the position of the producer.

Sliding of the retorts and leakages of air through the front walls are prevented in my furnaces by the employment of a covering of 85 cement 12, in which are embedded the horizontal iron bars which hold in place the cast-iron mouthpieces of the retorts. The ends of these bars are held by small bands of iron riveted to the stanchions and other supporting-ironwork of the retort-bench. This supporting-ironwork does not project at all beyond the face of the retort-bench, which is a great advantage when the removal of the coke 90 is effected with wagons or a quenching-conveyer.

I prefer to arrange the ascension-pipes and hydraulic main for inclined retorts in a manner which differs entirely from what has been heretofore employed. In retort-benches for illuminating-gas the ascension-pipes which convey the gas from the retorts to the hydraulic main are usually arranged vertically, whether the hydraulic main is placed in front or not of the face of the benches or furnaces. 100 The result of this is that the weight of the pipes acts directly on the cast-iron mouthpieces and tends to detach them from the retorts. Furthermore, these pipes being very close to the face of the bench or furnace are 105 greatly heated thereby, and the tar deposited in them forms accumulations which prevent the free escape of the gas. To obviate these inconveniences, known to every gas-works manager, I incline the ascension-pipes and 110 place the hydraulic main at a tolerable distance from the benches or furnaces. By these means the weight of the ascension-pipes acts much less powerfully on the mouthpieces of the retorts, and as the pipes diverge from the 115 face of the furnaces their contact with the cold air prevents the deposit of the tar in them and the obstructions occasioned thereby.

It is obvious that instead of contributing to the sliding downward of the inclined retorts the pipes oppose such sliding, since they bear against the face of the furnace by the intermediary of the small feet cast on the upper part of the cast-iron elbows a little below the cleaning-plugs n. (See Fig. 1.)

120 For ovens of great production, in which the obstruction of the pipes for the calcination of

the tar is to be feared in particular, it is well to increase the refrigerating action of the pipes by furnishing them with wings.

Having now particularly described and ascertained the nature of the said invention and in what manner the same is to be performed, I declare that what I claim is—

1. In a regenerative gas-furnace for inclined gas-retorts, the combination of a gas-producer, placed directly below one of the retorts of the furnace, said gas-producer being provided with a charging-opening placed at the level of the retort-charging floor, and at the side opposite that at which the coke is taken from the retorts, a combustion-chamber 5 placed behind the gas-generator, and a wall N separating the combustion-chamber and gas-producer, said wall being provided at its upper part with one or more openings *o* which allow the gas to pass into the combustion-chamber so as to heat strongly the lowest extremity of the retorts, substantially as described.
2. In a regenerative furnace, the combination with the inclined retorts, the recuperators, the gas-producer and the combustion-chamber 5, arranged below the lower ends of the inclined retorts and behind the gas-producer and separated from the gas-producer by the wall N having holes *o* and a wall M reaching to the arch of the furnaces and separating the working body of the furnaces, so as to compel the flames to pass between the supporting-walls of the retorts and to change direction four times before arriving at the recuperators, substantially as described.
3. In a regenerative gas-furnace having inclined retorts, the combination with the gas-

generator, the combustion-chamber 5 and the separating-wall, a hot-air inlet 8 admitting air below the lateral retorts from the bottom 40 and near the middle of the course of all the flames, so as to burn the excess of gas contained by them and thus to bring the highest end of the retorts to a sufficient temperature.

4. In a regenerative gas-furnace having inclined retorts, the combination with the gas-producer, the combustion-chamber 5, the separating-wall M and the second air-admission port, of a small hot-air inlet, the air coming in by the front wall of the gas-producer at 45 each side of the charging-mouth, for the purpose of increasing the temperature of the gas which is above the layer of fuel in the gas-generator.

5. In a regenerative gas-furnace for inclined 55 gas-retorts, the combination of a cement mantle or covering, in which the flanges of the retort-heads are sunk, together with horizontal iron braces, also sunk in the cement mantle, for the purpose of preventing the retorts 60 from sliding forward.

6. In a regenerative gas-furnace for inclined retorts, the combination of a hydraulic main or condenser placed before the body of the furnace with inclined pipes connecting said 65 main with the retort-heads, substantially as described.

In witness whereof I have hereunto set my hand in presence of two witnesses.

EUGÈNE DERVAL.
